US00D966669S

(12) **United States Design Patent** (10) Patent No.: **US D966,669 S**
(45) Date of Patent: **** Oct. 18, 2022**

- (54) **SHOE**
(71) Applicant: **adidas AG**, Herzogenaurach (DE)
(72) Inventor: **James Thompson**, Herzogenaurach (DE)
(73) Assignee: **adidas AG**, Herzogenaurach (DE)
(**) Term: **15 Years**
(21) Appl. No.: **29/777,634**
(22) Filed: **Apr. 7, 2021**

(57) **CLAIM**

The ornamental design for a shoe, as shown and described.

DESCRIPTION

FIG. 1 is a side view of a shoe.
FIG. 2 is another side view of the shoe of FIG. 1.
FIG. 3 is a front view of the shoe of FIG. 1.
FIG. 4 is a back view of the shoe of FIG. 1.
FIG. 5 is a top view of the shoe of FIG. 1; and,
FIG. 6 is a perspective view of the shoe of FIG. 1.
The dash-dot dash broken lines surround portions of the shoe that form no part of the claimed design.

1 Claim, 6 Drawing Sheets
